TOY RACECOURSE BOWL

Charles F. Nowlin, 2 Tara Lane, Worcester, Mass.

Filed May 19, 1959, Ser. No. 55,975

Term of patent 14 years

(Cl. D34—5)

Fig. 1

I claim:

The ornamental design for a toy racecourse bowl, as shown.
